SPECIALTY SHOE MACHINERY & TOOL COMPANY, OF ST. JOSEPH, MISSOURI, A
CORPORATION OF MISSOURI.

SHOE-NAILING MACHINE.

1,015,323.

Specification of Letters Patent. Patented Jan. 23, 1912.

Application filed March 18, 1909. Serial No. 484,114.

To all whom it may concern:

Be it known that we, LAWRENCE E. JOHNSON and JOHN CROWE, citizens of the United States, residing at St. Joseph, in the county of Buchanan and State of Missouri, have invented certain new and useful Improvements in Shoe-Nailing Machines, of which the following is a specification.

Our invention relates to apparatus employed in the manufacture and repair of shoes and has particular reference to shoe nailing machines.

The paramount object of the improvements which form the subject matter of this application is to provide an apparatus for the purpose specified so designed and arranged that nails of various sizes may be used in the same apparatus without changing or substituting any of the parts. Subsidiary to said prime object and for the purpose of accomplishing the desired result in a practical and convenient manner, we furnish the appliance with a novel and serviceable nail receptacle or hopper having a plurality of nail holding cells or pockets for containing the various sizes of nails, and group these pockets about a central pivoted support, the arrangement permitting the pockets to be brought in sequence to the feeding mechanism so that the particular size of nail desired will be fed to the hammer sleeve, while all the other cells or pockets will be kept out of service until the hopper is again rotated to bring another cell into operative position.

Other objects of the invention are to provide an improved nail feeding mechanism; to furnish in connection therewith means for operating the anvil in proper sequence; and to produce the necessary locking devices for retaining the multiple hopper in proper relation with the feeding channel, and in addition to supply means for automatically clearing the feed channel of the nail or nails contained therein, when it is desired to change the size used.

Further objects of our improved nailing machine are:—to furnish novel and efficient nail selecting means; to provide a guard to prevent the nails from lodging or clogging in the more contracted portions of the receptacle, and to arrange the coöperating parts of the feed mechanism and the actuating member so that it will be impossible to

feed two nails together to the hammer face, 55 as may happen in machines of the common type.

We accomplish the desired results above mentioned, and others of importance by employing the mechanism illustrated in the accompanying drawing, which forms a part of this application, and in which the important details of the entire machine, and particularly those embodying our novel improvements are disclosed in the following views, 60 65

Figure 1 is a side elevation of a shoe nailing machine incorporating all the features of the invention; Figs. 2 and 3 are front and side views, respectively, of the rocker block and rocker with attachments; Fig. 4 is an end elevation of the parts shown in Fig. 1 with the hopper and anvil removed, and some portions broken away; Fig. 5 is a top plan view of the mechanism illustrated in Fig. 1 with the hopper shown in dotted outlines; Fig. 6 is a top plan view of the multiple hopper detached from its support, two of the pocket lids being removed, and Fig. 7 is a sectional view taken on the line 7—7 of Fig. 6. 75 80

Referring to the details of the drawing, the numeral 10 indicates an oblong bed plate or table supported upon suitable standards or legs 11, secured to the said table by bolts or screws 11^a. Near one end of the table the latter is pierced by an upright slideable anvil rod 12, supported below the table by a collar 13, fixed to one of the legs 11. Upon the upper projecting end of the anvil rod is mounted an anvil 14, bent into a suitable curve of the usual shape, the free end terminating in a face 15. 85 90

At about the middle of the table 10 is erected a mast 16, stepped at the lower end in a boss 17^a. In the median line to the rear 95 of said mast is a vertical flat bar or plate forming a pressure head 17, and furnished with arms 17^b, 17^c, at the upper and lower ends respectively, which have enlargements 18, bored to slidably engage the said mast 16, so that the said pressure head has a limited movement in a vertical direction. To further guide and support the head 17, the lower arm 17^c extends rearwardly, and has fixed therein a stud or pin 19, which slides in and through a boss 17^a cast with the table 10. The said pressure head is restrained in its lower position by a spring 20, attached 100 105

to ears 20^a, 20^b, on the head and table respectively. The said upper arm 17^b of the pressure head 17 is supplied at the end with a cylindrical boss or barrel 21, in which is removably secured the stem of a hollow sleeve 22, and through this passes the hammer body hereinafter described. The said sleeve 22 is firmly fixed in position by means of a set screw 23. The said upper arm 17^b of the pressure head 17, bears a lug or projection 24, to which is firmly fixed a rocker block 25, secured to said projection 24 in such a manner as to extend at an angle with the arm of the pressure head, as shown best in Figs. 4 and 5. This block 25 is secured to the part 24 by a screw 26, which passes through a hole 25^a, and the block then takes a nearly horizontal direction terminating in a vertical projection provided with a flat face 27 slightly inclined from the perpendicular, the inclination being evident in Figs. 1 and 3. Against this face 27 is applied a rocker plate 28 having its lower portion cut away forming a notch to admit the horizontal body of the rocker block. The part below said notch is pivotally attached to the first portion of the rocker block by a screw 29. The upper portion of the rocker 28 is furnished with a median slot or notch 28^a which extends to the upper margin of said rocker. The latter is supplied upon one margin with an eye 30, to which is secured the upper end of a spring wire or buffer 31, the function of which will be hereinafter disclosed. The said wire is bent at the point 32 near its upper end and extends in a straight line to the pivot screw 29, around which it takes one or two turns to give sufficient resiliency, and then extends horizontally, being bent at 33 to form a hook which engages beneath a finger 30^a formed on the lower portion of the rocker 28. (Figs. 2 and 3.)

Located at one side and slidable in a slot in the margin of the table is a driving arm 34, having its lower end extending below the table level and provided with a horizontal arm 34^a, which terminates in a collar 35, slidably engaging the anvil rod 12, since this is conveniently situated to form a guide therefor. A boss or lug 36 on the side of the arm 34 forms a stop which engages the under side of the table to limit the upward movement. A lifting lug 37 is attached to the side of the arm 34 and extends below the upper arm 17^b of the pressure head 17, between that member and the mast 16, and its office is to lift the pressure head when the driving arm 34 is moved upwardly. The said driving arm 34 is operated by a rod 38, connected in the usual manner with the operating means (not shown), and having threaded attachment with a fork or yoke 38^a, secured to the said arm 34^a by means of a cotter pin 39. The driving arm 34 is main-

tained at its upper or initial position by a spring 40 attached to an ear on the bearing or collar 13, the other end being secured to the operating means in the usual manner (not shown). To the upper end of the pressure head 17 is attached an arm 40^a, which extends at an angle with the median line and has mounted upon the extreme end a spindle 40^b, said arm and spindle forming a support for a multiple nail hopper designated in its entirety by the reference numeral 41. Said hopper comprises a sleeve 42, rotatably mounted upon said spindle and formed integral with a spider consisting of arms 42^a radially arranged and merging into a series of triangular receptacles or pockets 43, grouped symmetrically about the spider, and arranged in such relation therewith as to form a substantially rectangular structure shown best in the plan view, Fig. 6. We prefer to cast the pockets and spider in a single mold, forming one piece. The side walls 43^a of the said pockets or cells converge toward the bottom and in the angle thus formed is milled a longitudinal slot 44, which extends to the apex of the pocket, and is open through the margin thereof. Near said apex of each pocket the slot 44 is guarded upon each side by inclined flanges 43^b, and the side walls 43^a of the pockets are extended forwardly and downwardly parallel with each other to form a continuation of the slot 44, termed the race-way, the extensions of the walls being designated by the reference characters 43^c, 43^d. The said pockets are furnished with covers or lids 45, hinged to the spider at 46, and provided with spring catches 47, their springs being shown at 47^a.

Upon the point or apex of each cover or lid 45 is mounted a trip consisting of a bent lever 48, pivoted at 49 in ears 50 attached to the said lid. Between the rear end of the trip 48 and the lid is interposed a spring 51, which normally depresses the forward end of said trip, so that it lies in contact with the upper margins of the race-way walls 43^c, 43^d. The object of this trip is to press upon the heads of the nails contained in the race-way at all times, except when the corresponding pocket is in operative position, and thus hold the said nails from sliding down the incline so long as that particular race-way is out of service. As will be seen by reference to Fig. 1, the upper end of the rocker block 25 is rounded to form a cam face 52, which will raise the trip as the hopper is rotated and hold it elevated so that the nails may pass down freely, so long as the operative position is maintained.

It will be understood that the hopper is revolved by hand to bring the required pocket into operative position, and to lock the hopper in such position we provide a latch member 53, pivoted at 54 to a projec-

tion 55 on the block 25, and held in operative position by a spring 56, interposed between the lower end of said latch member and the face of the upper end of the rocker block 25, the location of said spring being shown in Figs. 1 and 3. Upon one margin of the said latch member is a projection 57 which extends entirely through the upper vertical end of said rocker block, and is so arranged 10 as to enter the said slot 28^a in the rocker 28, the relation of this member being shown in full lines in Figs. 1 and 2, and in dotted outlines in Fig. 3. The upper end of this latch lever is provided with a lip or catch 58 which projects normally into the path of the corners of the hopper as it is swung upon its center, and is adapted to engage notches 58^a in the outer walls of the pockets, a portion of the lid being cut away for this 15 purpose, thus holding the hopper in operative position. To release the catch 58 the operator presses with his finger upon the lower end of the member 53 (see Fig. 3) raising the lip or catch so that it will clear the hopper as the latter turns. The said member 53 has two functions, the locking action above described, and a nail retracting office, carried out by the said projection 57, which will push out or retract a nail, if 20 one occupies the nail slot 28^a, whenever the hopper is turned, restoring that nail to its proper race-way, to make room for the desired size of nail which will enter the slot when the next pocket is brought into proper 25 relation therewith.

A nail duct or tube 59 (Fig. 1) extends between the horizontal portion of the rocker block and the barrel or sleeve 21, its upper end being continuous with a channel or conduit 59^a formed in the vertical projection of the rocker block 25. This conduit 59^a lies entirely within the block 25 throughout the lower part only of its course, the upper portion being open to the said face 27, but is 40 covered to form a closed channel by the said plate or rocker 28, except when the latter is operated to bring the slot 28^a to a position where it will register with said conduit.

By reference to Figs. 2 and 3 it will be 50 seen that the projection 57 passes to one side of the conduit 59^a, so that it will enter the slot 28^a when the latter is in its initial position.

The upper end of the pressure head 17 extends in a diagonal direction to a point directly over the barrel 21, and the extremity formed into an eye or collar in which is adjustably mounted a hammer rod 60, secured in said collar by a set screw 60^a.

Connected to the upper arm 17^b of the pressure head is a finger operating lever 61, Figs. 1 and 5, having attached to its upper end a stud 62, which passes through and is pivoted in the said arm. The projecting 60 end of this stud is provided with a trans-

verse pin 63, projecting upwardly at an angle to be engaged by a hook 64, attached to the driving arm 34. The lower end of said lever 61 is bifurcated to form a fork 61^a, in which is pivoted the lower end of a curved nail selecting finger 65, urged by a spring 66 against an anti-friction guide roller 67, journaled in a bracket 68, secured to the upper end of the pressure head by screws 69. A spring 61^b attached at its lower end to the said lever 61 and at its upper end to the projection 24, tends to rock the said lever on its pivot 62, and thus project the free end of the finger 65, guided by the roller 67, into the slot 44 in the pocket 43, directly thereover, this movement being permitted only when the pin 63 is released from engagement with the hook 64 by the downward movement of the operating arm 34, which carries said hook, as hereinbefore stated.

At a suitable distance above the table the operating arm 34 is provided with an angular reinforcement in which is mounted a stop screw 70. The point of the screw projects through said reinforcement and is adapted to engage the boss 17^a in which the mast 16 is stepped, the upper margin of said boss being properly beveled to form an engaging face. Beneath the head of the stop screw 70 is placed a suitable lock spring 70^a to prevent the screw from working loose from the jaw of the hammer.

The mechanical operation of the machine disclosed in the foregoing description is substantially as follows: It will be understood that the pockets of the multiple hopper will be partially filled with nails of the desired sizes, and the hopper turned until a selected pocket is locked in operative position by means of the latch 58 which will automatically engage the corresponding marginal notch 58^a. The nails will occupy the depressed portion of the pockets and as they are thrown in they will lie in various positions and some of them will fall within the slot 44, being retained by the engagement of their heads with the slot margins in a manner commonly made use of in appliances of this description. The anvil having been attached to its rod and the work placed thereon in the ordinary way, the operator depresses the rod 38, (the means employed not being shown in the drawing) and thus causes the driving arm 34 to move downward. Several mechanical movements will result, synchronously and in sequence; the descent of the driving arm will cause the hook 64 to release the pin 63, and this will allow the spring 61^b to act upon the lever 61 and thrust the finger 65 through the slot 44 in the direction of movement carrying any nails that may be suspended in the slot toward the upper part or apex of the pocket. Repeated thrusts of this selecting finger will soon fill 120 125 130

the slot with nails and the first nails in the row will be forced into the race-way whence they will slide by gravity down the incline until they reach the rocker plate 28. 5 If the latter is in its initial position the slot 28^a will register with said race-way and the first nail will fall into said slot, where it will remain until the rocker is moved to its second or alternate position. This movement 10 is a slight one just sufficient to carry the slot 28^a into registration with the conduit 59^a, so that the nail will enter that duct and thence pass into the tube 59 and be delivered to the nailing point in the sleeve 22. This rocking 15 movement of the plate 28 is caused by the engagement of the wire 31 at the point 33 by the end of the driving arm at the termination of its downward stroke, and the said plate or rocker 28 is restored to its first 20 or initial position, at the end of the up stroke by the engagement of the same member with the said wire 31 near the point 32. The rocker will now receive another nail in its slot 28^a, when the action is repeated. Since 25 the plate 28 is operated at the extreme end of the stroke only, in either direction, it will be impossible to feed two nails to the nailing point at the same time, for if the operator fails to bring the driving arm to the extreme 30 limit up or down, the plate 28 will be unaffected. When the lip 58 is in engagement with the notch 58^a the projection 57 is retracted sufficiently to allow the plate 28 to be rocked, but when said lip is raised to permit 35 the hopper to be rotated, the said projection will enter the slot 28^a, forcing back the nail therein and restoring it to its race-way, thus preventing the feeding of a nail of improper size. The hammer 60, being attached 40 to the end of the driving arm descends therewith, the depth of the nail relatively to the work being regulated by the screw 70 which governs the downward limit of the driving arm. As the latter descends 45 the lug 37 will release the pressure head 17 permitting the spring 20 to act and bringing the sleeve down firmly upon the work.

It may happen that the slot 44 in the bottom of the pocket 43 and the race-way will 50 be wholly or partially filled with nails and interfere with the full movement of the finger 65, in which case it will move only a part of its stroke, since its actuating member is a spring. Upon the up stroke of the driving 55 arm, the hook 64 will engage the pin 63 and restore the finger 65 to the retracted position shown in Fig. 1, the lug 37 raise the pressure head, lifting the sleeve 22 from the work, and the end of the driving arm will strike 60 the lower end of the buffer 31 and rock the plate 28 back to its first position. If, for any reason, the nail should lodge between the raceway and the rocker so as to clog the latter, as might happen if the nails were oily 65 or gummy, the end of the spring 31 will yield

when struck by the operating member, and prevent damage from the impact.

Having thus described our invention, what we claim is:—

1. In a shoe nailing machine, the combination with nail driving mechanism, of a rotatable nail hopper, a plurality of triangular pockets in said hopper, each pocket being provided with a longitudinal slot in its bottom, a nail-selecting finger arranged below said hopper, and adapted to be projected into said slot, means for projecting the finger into the slot, and means for retracting said finger. 70

2. In a shoe nailing machine, the combination with nail driving mechanism, of a rotatable nail hopper, having a plurality of pockets, each of said pockets having a longitudinal slot in its bottom, a lever pivoted below the hopper, a nail selecting finger attached at one end to said lever, and means for operating said lever to project the finger into said slot. 80

3. In a shoe nailing machine, the combination with nail driving mechanism and operative means therefor, of a rotatable hopper having a plurality of pockets adapted to be brought successively into operative position, means for locking the hopper when rotated, and nail feeding mechanism co-operating with said hopper, said feeding mechanism comprising a rock-plate provided with a nail slot, a nail conduit adjacent said plate, and the means for clearing said slot when said hopper is turned. 90

4. In a shoe nailing machine, the combination with nail driving mechanism including a driving arm, and operative means therefor, of a rotatable hopper having a plurality of pockets, each pocket provided with a longitudinal slot, a finger adapted to engage said slot when the pocket is in operative position, means for operating said finger, a rocker plate having a nail slot therein, said plate being adapted to be operated by said driving arm, means for locking the hopper in each of its operative positions, and means for clearing said nail slot when the hopper is unlocked. 105

5. In a shoe nailing machine, the combination with nail driving mechanism including a driving arm, and operative means therefor, of a hopper having a plurality of slotted pockets, said hopper arranged so as to bring the pockets in succession to an operative position, a nail selecting finger arranged below the hopper, means for operating said finger, nail feeding mechanism comprising a rock plate having a nail slot therein, said plate being arranged to be operated by said driving arm at each end of its stroke, means for locking the hopper in any of its operative positions, and means for clearing said nail slot when the hopper lock is released. 115

6. In a shoe nailing machine, the combination with nail driving mechanism, including a driving arm and operative means therefor, of nail feeding means comprising a rocker plate adapted to be operated by the said driving arm, said plate having a nail slot therein, a conduit arranged adjacent to said plate, a buffer on said plate arranged to receive the impact of the said driving arm, and means for clearing said nail slot.

7. In a nailing machine, including nail driving mechanism, and operative means therefor, the combination with a slotted nail receptacle, of a finger arranged below the receptacle and adapted to be projected into said slot, means for operating said finger, nail feeding mechanism, comprising a rocker block, a rocker plate pivoted on said block and having a nail slot therein, a nail conduit arranged adjacent to said plate, and means for rocking said plate so as to bring the nail slot alternately into registration with the slot in said pocket and said conduit.

8. In a nailing machine, including nail driving mechanism, and operative means therefor, the combination with a nail receptacle having a longitudinal slot therein, of nail selecting means comprising an operating lever, a spring attached to the lever, and a finger pivoted to said lever and adapted to engage said longitudinal slot, and means for restoring said finger to its initial position.

9. In a nailing machine, the combination with nail driving mechanism and operative means therefor, of a nail receptacle having a longitudinal slot in its bottom, a finger ar-

ranged below the receptacle and adapted to be projected into said slot, means for operating said finger, a race-way in alignment with said slot, a rocker plate arranged transversely to said race-way, and provided with a nail slot, a nail conduit adjacent to said plate, and means for rocking said plate to bring said nail slot alternately into alignment with said race-way, and the nail conduit.

10. In a nailing machine including nail driving means, the combination of a rotatable hopper having a plurality of nail receptacles, each receptacle having a longitudinal slot in the bottom, a nail selecting finger adapted to engage said slot, means in said receptacle for guarding the slot, a race-way in alignment with said slot, and operative means for said finger.

11. In a nailing machine, including a nail driving arm, the combination of a rotatable hopper, a plurality of nail receptacles in said hopper, each receptacle having a longitudinal slot in the bottom, a finger operating lever arranged below the hopper, a nail-selecting finger pivotally attached to said lever and adapted to be projected through said slot, and means attached to the nail driving arm for operating the said lever.

In testimony whereof we affix our signatures in the presence of two witnesses.

LAWRENCE E. JOHNSON.
JOHN CROWE.
